ALFRED R. ANTHONY, OF MONTROSE, PENNSYLVANIA, ASSIGNOR, BY MESNE ASSIGNMENTS, TO DAVID V. SUTTON, OF MADISON, NEW JERSEY.

LIQUID-FUEL BURNER.

1,071,381

Specification of Letters Patent. Patented Aug. 26, 1913

Application filed July 13, 1912. Serial No. 709,212

To all whom it may concern:

Be it known that I, ALFRED R. ANTHONY, a citizen of the United States, and resident of Montrose, Susquehanna county, State of Pennsylvania, have invented a certain new and useful Improvement in Liquid-Fuel Burners, of which the following is a specification.

This invention relates to fuel oil burners and has for its object the production of a burner which is simple in construction, is thoroughly efficient in operation and may be conveniently installed.

Other objects and the features of novelty will be apparent from the following description, taken in connection with the accompanying drawings, in which,

Figure 1 is a plan view of a burner shown in connection with a scrubber or strainer for the fuel oil; Fig. 2 is a vertical longitudinal section through the burner; Fig. 3 is an enlarged transverse section on the line 3—3 of Fig. 2; Fig. 4 is a transverse section on the line 4—4 of Fig. 2; Fig. 5 is a fragmentary longitudinal section of a modified form of nozzle; Fig. 6 is a fragmentary section of still another form of nozzle; Fig. 7 is a view similar to Fig. 3 and showing a modified form of cone plug for dividing the spray.

Referring to the drawings, 10 indicates the burner casing which is provided preferably on its lower side with an air inlet 11 and has the nozzle end 12 thereof externally screw-threaded to receive an adjustable cap 13. The cap 13 may be provided with the outward projections 14 by means of which it may be conveniently rotated and a lock nut 15 may be arranged on the threaded end 12 to lock the cap 13 in position. The rearward end of the casing 10 is internally screw-threaded as at 16 to receive the spindle or pipe 17 which extends longitudinally through the interior of the casing. The spindle 17 may have its outer end provided with an angular flange 18 which is adapted to receive a wrench for the purpose of adjusting the pipe. The nozzle end of the pipe 17 is preferably reduced and provided with external threads as at 19, on which may be arranged a sleeve 20 which may be conveniently locked in position by a suitable nut 21. Rearwardly of the threaded portion 19 of the spindle or pipe 17 is an enlarged portion 22 which may be externally screw-threaded to receive a cap 23, the lat-

ter being provided with internal longitudinally extending ribs 24 which engage the threads on the enlarged portion 23.

The spindle or pipe 17 is provided with a longitudinal bore which is preferably conical in the reduced end portion 19 and rearwardly of this conical portion there is an enlarged cylindrical portion 25 and rearwardly of the portion 25 is a still larger portion 26. At its outward end the spindle or pipe 17 may be internally threaded to receive the sleeve 27 provided with a flange 28 and having arranged thereon a ring nut 29 by means of which a fitting 30 is secured to the sleeve 27. The fitting 30 is provided with a laterally extending tubular portion or elbow 31 which is connected with an elbow 32 on the scrubber or strainer 33 by means of a union 33^a, which may be of any usual construction. The tubular portion 31 of the fitting 30 communicates with the interior of the latter and thus with the interior of the spindle or pipe 17.

A needle valve 34 extends longitudinally of the bore of the spindle or pipe 17 and has a conical or pointed end 35 which co-operates with the conical bore of the reduced end of the spindle to regulate the flow of oil therethrough. The nozzle valve may be provided with a shoulder 36 and a ring or collar 37 may be arranged on the needle valve between this shoulder and the conical end 35 to act as a support for the latter. The ring 37 is provided with a series of longitudinal openings 38 which permit the oil to pass therethrough.

The fitting 30 has secured thereto by means of the screw threads 39 a bonnet 40 which is internally screw-threaded as at 41 and in engagement with the threaded portion 42 of the needle valve. At its outer end the bonnet 40 is provided with a suitable cap or gland 42^a which co-operates with the bonnet to form a chamber for the packing material 43, this packing material preventing the leakage of oil along the stem of the needle valve. Externally of the bonnet 40 the needle valve is provided with a suitable hand wheel 44, by means of which the valve may be adjusted.

As shown in Fig. 1, the nozzle end of the spindle or pipe 17 is internally screw-threaded as at 45 to receive the plug or tip 46 which is provided at one end with a conical bore 47 and at the other end with a

preferably straight bore 48 in line with the point of the needle valve 35. The conical bore 47 is, as shown, slightly larger than the adjacent portion of the conical bore in the end of the spindle 17. By this arrangement there is no possibility of the point of the needle valve engaging the plug or tip 46 and unscrewing the same.

A tubular member 49 has screw-threaded engagement with sleeve 20 and in Fig. 1 which is the preferred form of the invention, I have shown this member as engaging threads on the interior of said sleeve. A conical plug 50 having a plurality of wings 51 is arranged on the interior of the member 49 and secured to the latter by means of screw threads.

The plug or tip 46 has a conical outer end which projects into a corresponding conical bore 52 in the inner end of the member 49. The sleeve 20 is provided with a series of radial openings 53 which register with the space between the plug 46 and the inner end of the member 49. From a point adjacent the outer end of the plug 46 the member 49 is provided with an outwardly flaring bore 54 in which is arranged the cone plug 50. The outer end of the member 49 is conically formed, as at 55, and cooperates with the conical end 56 on the cap 23 to form a conical space 56^a through which air may be discharged from the chamber between the cap 23 and the sleeve 20. The cap 13 has its outer end conically formed to cooperate with the end 56 of the cap 23 to form another conical space 56^b through which air may be discharged from the space between the end portion 12 of the casing 10 and the cap 23. The plug 50 is extended outwardly beyond its conical portion and is provided with the circumferential groove 57 which is opposite the conical space 56^a. The shape of the groove 57 is such that the jet which is discharged through the space 56^a will be converted into an outwardly flaring cone. Beyond the groove 57 and opposite the space 56^b is a second circumferential groove 58 which may be similar in shape to the groove 57.

50 The operation of the burner is as follows: The oil flows through the scrubber or strainer 33 and the elbows 32 and 31 into the interior of the fitting 30. From the latter the oil flows longitudinally through the 55 annular space between the needle valve 34 and the spindle or pipe 17 to the collar 37 and then through the openings 38 in the latter to the conical end portion of the spindle. The needle valve being slightly 60 open the oil will flow past the point 35 of the needle valve and through the bores 47 and 48 of the plug 46 and against the pointed end of the plug 50. This pointed end will form the jet of oil into a cone.

65 Air under pressure is received in the casing

10 through the inlet 11 and passes into the annular spaces between the caps 13 and 23 and the cap 23 and the sleeve 20. From the latter space the air passes through the openings 53 and flowing along the conical outer end of the plug 46 will be discharged in the form of a converging conical jet against the jet of oil discharged from the tip 46. The jets of oil and air will meet in the bore 54 of the member 49 and the oil will be somewhat atomized and mixed with the air. The mixture will flow along the exterior of the conical plug 50 as an outwardly diverging conical sheet. This outwardly diverging conical sheet will be met by the inwardly directed conical jet of air discharged through the space 56^a driving the mixture into the groove 57 and more thoroughly break up the particles of oil and atomize the same and form a more perfect mixture. The mixture will be turned outwardly by the groove 57 in the form of a diverging conical sheet which will be met by the jet of air discharged through the space 56^b, this jet driving the mixture into the groove 58 and effecting a more perfect atomization of the oil, whereby the latter will more readily combine with the air to form a perfect mixture. The groove 58 will again turn the mixture outward in the form of a diverging conical sheet which will leave the plug 50 and owing to the shape of this plug will be distributed through the furnace in a lateral direction thereby effecting a thorough distribution of the flame throughout the furnace.

The pointed end of the plug 50 serves as a means for breaking the jet of oil which is discharged from the plug 46 into a thin sheet and therefore the burner will be adapted to use very thick oils since this means for positively separating the jet causes the latter to be thoroughly broken up by the jets of air which will impinge upon it.

It is sometimes desirable to project or drive the mixture longitudinally of the furnace and in order to accomplish this the outer end of the plug 50 is provided with a cone. Referring to Fig. 5, it will be seen that I have illustrated the nozzle end of the burner, the parts being the same with the exception that the plug 60 which corresponds to the plug 50 in Fig. 2, has a pointed or conical end 61 so that the jet of air discharged through the space 56^b will drive the mixture inwardly in the form of a converging cone which on leaving the point of the cone 61 will be directed through the furnace in the form of a pencil or jet.

When some classes of fuel are used only two jets of air are necessary to form a perfect mixture and therefore the jet formed by the space 56^b may be dispensed with. Under these circumstances the sleeve 23 may

be eliminated and the end of the cap 13 made to coöperate with the outer surface of the member 49 to form the space 56^a, as shown in Fig. 6. In this construction the end of the plug 50 may be in the form of a cone, as in Fig. 5, or may be provided with the spreader at the end, as shown in Fig. 2.

I have shown in Fig. 7 a modification in which the plug instead of having wings 51 which engage screw threads on the inner surface of the member 49, as shown in Fig. 2, may be provided with an internally threaded flange 62 which engages the external threads on the plug 63, the latter having a screw threaded connection with the interior of the sleeve 20. In this construction the plug 63 takes the place of the member 49 and the flange 62 on the plug coöperates with the cap 23 to form the space 56^a. The flange 62 has openings 64 in alinement with the surface of the conical plug against which the oil is discharged. Otherwise this modification may be similar in all respects to that shown in Fig. 2.

While I have shown in Fig. 6 a burner in which the cap 23 is omitted to provide a single jet 56^a, and in Figs. 2, 5 and 7 burners having the cap 23, to provide the two jets of air 56^a and 56^b, it will be obvious that two or more superposed caps 23 and the corresponding number of grooves in plug 50 may be employed to provide three or more jets similar to jets 56^a and 56^b.

By having the fitting 30 connected with the spindle 17 in the manner illustrated in Figs. 1 and 2, it will be evident that this fitting may be swung so that the elbow 31 stands in any desired position and the fitting may be securely held in this position by means of the nut 29. It will also be seen that the nozzle may be readily taken apart by uncoupling the union 33^a and by unscrewing the spindle 17 from the body 10. This permits the spindle and the cap 23 and all of the parts carried thereby to be removed without disturbing the casing 10. The parts may also be returned to their former positions after being taken out as the adjustment need not be disturbed in removing them. The needle valve may also be readily removed by unscrewing the bonnet 40 from the fitting 30. The cap 23 may be adjusted to make the space 56^a any desired width, while the spindle is out of the casing 10 and the cap 13 may be readily adjusted without disturbing the adjustment of the cap 23. If desired, the cap 13 may be adjusted so as to be in contact with the cap 23 and thereby close the space 56^b whenever desired.

By having the plug 46 removable from the spindle 17, it is possible to use plugs having the bore 48 of different sizes so as to discharge different quantities of oil. This arrangement obviates the necessity of

renewing the whole spindle in order to provide a different outlet opening at the end of the needle valve.

It will be obvious to those skilled in the art that various changes may be made in the details of the invention within the scope of the appended claims and therefore I do not wish to be limited to the precise details of construction shown and described.

Having thus described my invention what I claim is:

1. In a burner, the combination of a nozzle, means for supplying fuel to the nozzle, means for regulating the discharge through the nozzle, means for discharging a jet of air against the stream of fuel immediately after the fuel leaves the nozzle, a conical member arranged in alinement with the nozzle and adapted to form the mixture of fuel and air into an outwardly diverging conical stream, means for discharging a conical jet of air against said outwardly diverging stream to break up the outwardly diverging cone, and means for forming the mixture of air and fuel into a second outwardly diverging conical jet.

2. In a burner, the combination of a nozzle, means for supplying fuel to the nozzle, means for regulating the discharge of fuel through the nozzle, means adapted to form the jet of fuel discharged by the nozzle into an outwardly diverging conical stream, means adapted to deliver a conical jet of air against the conical stream of fuel to break up the latter, means for forming the stream into a second outwardly diverging cone, and means for discharging a second conical jet of air against said second outwardly diverging cone for breaking up the latter.

3. In a burner, the combination of a nozzle, means for supplying fuel to the nozzle, means for regulating the discharge of fuel through the nozzle, means for forming the jet of fuel discharged by the nozzle into an outwardly diverging conical stream, means for discharging a conical jet of air against the outer surface of the stream of fuel to break up the latter, means for forming the stream of fuel into a second outwardly diverging conical stream, means for discharging a second conical jet of air against said second conical stream to break up the latter, and means for forming the fuel into a third outwardly diverging conical stream.

4. In a burner, the combination of a nozzle, means for supplying fuel to the nozzle, means for regulating the discharge of fuel through the nozzle, a cone arranged in alinement with the nozzle and adapted to form the fuel discharged by the nozzle into an outwardly diverging conical stream, a nozzle for discharging a converging conical jet of air against the stream of fuel, and a circumferential groove in said cone opposite said air nozzle and adapted to form the fuel into

- a second outwardly diverging conical stream after the first stream has been broken up by the jet of air.
5. In a burner, the combination of a nozzle, means for supplying fuel to the nozzle, means for regulating the discharge of fuel through the nozzle, an adjustable cap surrounding the end of the nozzle and forming therewith an air chamber, means for supplying air to the chamber, means for discharging air from said chamber against the jet of fuel immediately after the latter leaves the nozzle, and a conical member carried by the nozzle and adjustable independently of the cap and adapted to form the mixture of air and fuel into an outwardly diverging conical stream. 40
- 10 6. In a burner, the combination of a nozzle, means for supplying fuel to the nozzle, means for regulating the discharge of fuel through the nozzle, a sleeve adjustably arranged on the outer end of the nozzle and projecting beyond the end of the nozzle, an adjustable cap secured to the nozzle and 45 forming an annular air chamber on the exterior of said sleeve and cooperating with the outer end of the sleeve to form a conical nozzle to discharge air from said chamber, and a conical member carried by said sleeve 50 on the interior thereof and adapted to form the jet of fuel into an outwardly diverging conical stream. 55
- 15 7. In a burner, the combination of a hollow spindle having a nozzle at its outer end, a valve extending longitudinally through said spindle and adapted to control the discharge of fuel through said nozzle, a cap adjustably secured on said spindle and providing 60 an annular air chamber surrounding said nozzle, a casing surrounding said spindle and forming an air chamber, and a cap on said casing surrounding said first-mentioned cap and cooperating therewith to form an outwardly converging conical space for discharging air from said chamber. 65
- 20 8. In a burner, the combination of a hollow spindle having a nozzle at its outer end, a valve extending longitudinally through said spindle and adapted to control the flow of fuel through said nozzle, means forming a mixing chamber beyond said nozzle, a cap secured to said spindle and forming with said means an annular air chamber surrounding the nozzle, a casing surrounding said spindle, and an adjustable cap on said 70 casing and cooperating with the first cap to discharge air from the interior of said casing in the form of an inwardly converging conical jet.
- 25 9. In a burner, the combination of a casing, a tubular member arranged longitudinally of the casing and having a nozzle at its outer end, a sleeve adjustably secured on the end of said tubular member and providing a mixing chamber beyond said nozzle, and a plurality of adjustable caps co-operating with said sleeve and with each other to form inwardly directed conical nozzles for discharging air from the interior of 75 said casing. 80
- 30
